UNITED STATES PATENT OFFICE.

EZEKIEL C. CONDIT, OF SILVERTON, COLORADO.

MINE VENTILATOR.

1,404,742.

Specification of Letters Patent. Patented Jan. 31, 1922.

Application filed April 4, 1921. Serial No. 458,418.

To all whom it may concern:

Be it known that I, EZEKIEL C. CONDIT, a citizen of the United States, residing at Silverton, in the county of San Juan and 5 State of Colorado, have invented certain new and useful Improvements in Mine Ventilators, of which the following is a specification.

The present invention relates to mine 10 ventilating apparatus and more particularly to a specially constructed furnace, or stove, having a combustion chamber through which passes the ventilator duct for removing dust and noxious gases from the tunnels, 15 shafts and other parts of a mine. The ventilator duct and the gases within the same at this point are thus brought to a high temperature before passing out to the atmosphere, thereby creating a draft in the duct. 20 The furnace will also serve as a means for heating the room or building in which the ventilator is located.

An important feature of the invention is the arrangement of the ducts, flues and other 25 parts of the ventilator, so that the gases from the ventilator duct and the products of combustion from the combustion chamber are discharged into a common up-take before passing to the atmosphere. The draft in 30 the ventilator duct is considerably increased in this manner, thereby assuring efficient ventilation of the mine. A fan located in the up-take of the ventilator also serves as a means for inducing a draft in the ventilator duct when the ventilator is first started, or it may be used alone when only a slight 35 draft in the duct is required.

Referring to the accompanying drawing, 40 wherein like reference numerals indicate the same parts throughout the several views,

Figure 1 represents a vertical sectional view of the ventilator, the ventilator duct being shown leading into the ventilator proper from a horizontal position;

Fig. 2, a fragmentary view, partly in rear elevation and partly in section taken on line 2-2 of Fig. 1, showing the arrangement of the fan in the ventilator;

Fig. 3, a fragmentary horizontal section 50 taken on line 3-3 of Fig. 1, and

Fig. 4, a fragmentary sectional view, showing the ventilator duct leading into the ventilator proper from a vertical position.

In the drawing, 1 represents the furnace 55 or stove body proper, supported by legs 2 attached to its base. The body of the fur-

nace 1 encloses a combustion chamber 3 about the lower portion of which extends the usual refractory lining 4. Extending beneath the combustion chamber is an ash 60 pit 5 having a grate 6 located just above the same. The combustion chamber is provided with a door 7 and the ash pit with a door 8, the latter having a draft regulator 9 mounted therein. 65

The top wall 10 of the combustion chamber is provided with a circular opening 11, and an opening 12 of the same size is provided in the rear of the furnace body 1. In these openings is mounted an elbow or 70 curved section of a ventilator duct 13, the same being supported in combustion chamber 3 from above by a flange 14 provided near the upper end of member 13. To the lower end of member 13 there is connected 75 the main portion 15 of the ventilator duct which leads into the part of the mine to be ventilated.

Above the combustion chamber 3 is a dome-shaped gas chamber 16 into which the 80 upper end of section 13 of the ventilator duct opens. This chamber is formed by two sections 17, 18 which are secured together by means of bolts and nuts 19 passing through ears 20 provided on the contiguous 85 edges of the sections for this purpose. Sections 17, 18 are supported by the top wall 10 of the combustion chamber, and an upstanding flange 21 about the upper edge of the furnace body 1 serves to locate the sections in proper position. Sections 17, 18 are 90 cut away at their upper edges so as to form an opening 22 for the gases passing through chamber 16. An upstanding flange 23 is provided on the sections about opening 22 95 over which a vertical smoke pipe 24 fits, the lower edge of the smoke pipe resting on the sections 17, 18.

In the top wall 10 of the combustion chamber at the rear of the ventilator and within 100 the angle formed by the walls of the combustion chamber and the ventilator duct there is provided an outlet 25 for the products of combustion to pass from combustion chamber 3 into gas chamber 16. A channel-shaped deflector 26 surrounds three sides of this opening 25 and is bolted to wall 10 through a flange 27 provided on its lower edge. Reflector 26 with sections 17, 18 of gas chamber 16 thus form a passage-way 26' 110 through which the products of combustion from chamber 3 are conducted to the upper

- part of chamber 16 above the discharge end of ventilator duct 13 and into smoke pipe 24, and thence to the atmosphere. The location of outlet 25 it is to be noted is such as 5 to cause the products of combustion to be drawn about ventilator duct 13 on their way to the atmosphere, thereby effecting a maximum heating of the duct and the gases therein.
- 10 Mounted horizontally in chamber 16 above the forward edge of the upper end of section 13 of the ventilating duct so as not to interfere with the draft through the ventilator duct is a fan 28 somewhat wider 15 than the open end of section 13 and oval-shaped so as to give it as much effective area as possible and yet allow it to operate without interference from the walls of chamber 16. Fan 28 is provided at one end with a 20 stub shaft 29 journaled in a bearing 30 provided on section 18 of the gas chamber 16 for this purpose, and at the other end with a stub shaft 31 provided with a removable crank 32 extending through an opening 33 25 in section 18.
- In operation a fire is built on the grate 6 in the bottom of combustion chamber 3 whereby section 13 of the air duct and the 30 gases therein are rapidly brought to a high temperature. A strong upward draft is thereby created through the air duct 15, section 13, gas chamber 16 and smoke pipe 24 as indicated by the arrows in Fig. 1 whereby 35 the foul air and other obnoxious gases are rapidly removed through duct 15, the outer end of which extends into any desired part of the mine. In Fig. 1, ventilation duct 15 is shown extending from a horizontal position for removing smoke and gas from the 40 tunnel of the mine, while Fig. 4 shows a modification, wherein a ventilator duct 15' is shown extending from a vertical position for removing the air from the mine shaft.
- The products of combustion from combustion chamber 3 pass rapidly from this chamber through opening 25, passageway 26' and out to the atmosphere through smoke pipe 24 due to the draft through the combustion chamber produced by draft regulator 9 in 45 ash-pit door 8 and the smoke pipe 24. It will be seen on reference to Fig. 1 that the products of combustion on their way to smoke pipe 24 are discharged from the upper end of passageway 26' at an upward angle, 50 as indicated by the arrows, into the stream of heated gases passing upwardly from section 13 of the ventilator duct into smoke pipe 24 through chamber 16, thereby considerably increasing both the upward draft 55 in chamber 16 above the open end of the ventilator duct and in smoke-pipe 24. While the use of fan 28 is not absolutely necessary, its operation at any time will accelerate the 60 flow of gases through ventilator duct 13. 65 It is particularly useful on damp days or

whenever it is desired to start a current flowing quickly; and in many cases, its use alone will create all the draft necessary without building a fire in the furnace.

The ducts and passageways of the ventilator it is to be noted are formed, wherever practicable, with gradual curves so as to interfere as little as possible with the natural and rapid upward flow of the gases and the production of strong drafts where 75 desired.

While the drawing illustrates a practical embodiment of the invention, which may be operated economically and with little personal attention it is contemplated that minor 80 structural changes may be made without departing from the invention as defined by the appended claims.

The term "up-take" as used in the claims is intended to include sections 17, 18 forming gas chamber 16 and smoke pipe 24, although it is not intended to restrict the invention to these means. Changes may be readily made in this part of the ventilator, the essence of which, however, is that the 90 products of combustion are discharged into the passage through which the gases from the ventilator duct are passing so as to increase the draft and facilitate the ventilation of the mine. 95

What is claimed is:—

1. The combination with a furnace structure having a combustion chamber provided with an outlet in its upper wall, of a casing forming a gas chamber above said combustion chamber into which the products of combustion pass through said outlet, said casing being also provided with an outlet 100 for the gases in said chamber; and a ventilator duct passing through said combustion chamber and discharging into the gas chamber beneath said gas outlet. 105

2. The combination with a furnace structure having a combustion chamber provided with an outlet for the products of combustion, of a casing forming a gas chamber above said combustion chamber into which the products of combustion pass through said outlet; a ventilator duct passing through the combustion chamber and discharging into the bottom of said gas chamber; means located in said gas chamber for conducting the products of combustion from the combustion chamber into the upper part of the gas chamber above the 110 open end of said ventilator duct; and a smoke pipe leading from an opening into the upper part of said gas chamber above the discharge end of said ventilator duct. 115

3. The combination with a furnace structure having a combustion chamber provided with an opening in its rear wall and an opening in its top wall, of a dome-shaped casing supported by said furnace and forming a gas chamber in conjunction with the 120 125

130

top wall of said furnace; a ventilator duct connecting the openings in the walls of the combustion chamber and discharging at its upper end into said gas chamber; and 5 means for conducting the products of combustion from said combustion chamber into the upper part of said gas chamber, said

gas chamber having an outlet in its top wall in line with the discharge end of the ventilator duct.

10

In testimony whereof I have signed my name to this specification.

EZEKIEL C. CONDIT.
